UNITED STATES PATENT OFFICE.

GEORGE HENRY DUNLOP, OF AUBURN, VICTORIA, AUSTRALIA.

EXCAVATING-MACHINE.

1,234,147.

Specification of Letters Patent. Patented July 24, 1917.

Application filed November 17, 1911. Serial No. 660,786.

To all whom it may concern:

Be it known that I, GEORGE HENRY DUNLOP, a subject of the King of Great Britain and Ireland, residing at No. 20 Robinson's 5 road, Auburn, in the British State of Victoria, Commonwealth of Australia, have invented new and useful Improvements in Excavating-Machines, of which the following is a specification.

10 This invention relates to excavating machinery of that type in which an excavating scoop or bucket is guided in its course across a cutting, such as a channel by runways, in which the scoop is suitably mounted on 15 wheels, and which runways are shaped to conform to the profile or transverse cross section of the cutting to be excavated.

The objects and nature of the invention will be readily understood by those skilled 20 in the art in the light of the following explanation of the accompanying drawings illustrating what I now believe to be the preferred embodiment from among other constructions and arrangements within the 25 spirit and scope of the invention.

The invention consists in certain novel features of construction and in combinations and arrangements as more fully and particularly set forth and specified hereinafter.

30 In the drawings:—

Figure 1, is a side elevation.

Fig. 2, is a part plan and

Fig. 3, a cross sectional elevation taken from line a, a Fig. 1, of a machine adapted 35 to be used with a double acting scoop, the runway frame being raised and lowered by means of gearing mounted on one side frame and gearing for propelling the machine, while,

40 Fig. 4, is a side elevation showing a single acting scoop and runway frames pivotally mounted at one side of the cutting and adapted to be raised and lowered on pivotally mounted struts on the other side.

45 Fig. 5, is a part elevation showing the runways supported on racks or screws supported on wheels on rails or on the ground, the axles of the wheels and the tops of the racks or screws on each side of the cutting 50 being connected together.

Figs. 6, 6^a, 6^b are side views of the scoop and part of the runways when the scoop is pivotally mounted on two wheels and operated by three ropes.

55 In Figs. 1 to 5, on the axles A there are wheels B resting on the ground or on suit-

able rails; these axles A have bearings E on side beams F with vertical channel irons J having bracing as K, K¹, K², said channel irons J being connected across at the top by 60 channel irons L, L¹. Each set of framing on wheels constitutes a side frame, one at each side of the excavation.

The runway frames consist of a pair of braced girders as G, having their lower 65 booms of channel irons as W, suitably shaped to conform to the profile of the cutting, with the flanges turned inward and forming runways for the wheels s, on which the scoop S is mounted. Upon the runway 70 frames there are pairs of angle irons M flanges outward fitting closely but easily one at each side of each channel iron J of the side frames forming a sliding connection 75 guiding the runways on the side frames, while on the axle A, or suitable framework, is a guide C which is free to move vertically in a channel iron c on the frame; or if desired two angle irons c¹, may be used as shown in Fig. 4. At each end of the runway frames the runways are enlarged into box-like chambers N, which constitute the reversing places in which the scoop is reversed. The framework comprising two 80 running frames suitably braced together and 85 carrying the scoop mounted in the runways is suspended from the side frames by two pairs of screws P, one pair at each side frame, connected to the runway frames by pins as p¹ through parts of the cross bracing 90 p², and passing through geared nuts T set between the pairs of channel irons L, L¹.

The scoop S is mounted on axles S¹ at each end having wheels s which travel between the flanges of the runway channel irons W. It is formed of a U shaped plate s¹ forming those parts which are alternately the bottom or top of the scoop (according to which way it is moving) and the curved back, side plates s² with bearings s³, attached at the front of the scoop and at the back of the scoop s⁴, for the axles. From the back of the scoop hauling ropes U extend each around a guide pulley V placed one at each end of the runway over the reversing places and thence to one of the winding drums x, placed on the machine as shown. There is a guide pulley V¹ placed at the center of the machine just clear above the space traversed by the scoop, under which the ropes U pass so as to render the pull on the scoop more effective when the scoop is on that half 105 110

of the machine farther from the end toward which it is traveling.

The means for hauling the scoop consists of a winding engine (not shown) operating 5 two drums α for hauling the scoop by means of the ropes U attached at the back or rear end of the scoop. If the winding drums are placed on the side frames there must be suitable direction pulleys to lead the ropes 10 to them.

The means shown for raising and lowering the runways comprises an engine Y on one of the side frames driving a crank shaft Y^1 with a conventional form of gearing 15 comprising a pair of bevel wheels y on the crank shaft driving either way, according to which is in gear, a bevel wheel y^1 on a vertical shaft Y^2 which carries a sprocket wheel Y^3 , driving chain y^2 to rotate the 20 geared nuts T , while on the top end of said vertical shaft Y^4 is one of a pair of bevel wheels y^8 , the other one of which drives a cross shaft y^9 which drives similar raising and lowering gear on the other side.

25 The means for propelling the machine comprises a set of bevel wheels y^3 in the other end of the crank shaft Y^1 similarly operating a bevel wheel y^4 on a horizontal shaft Y^4 which carries a sprocket wheel y^5 30 and thence by means of chain gearing y^6 of usual kind turning the sprocket wheels y^7 on the wheels B and so moving the machine either way according to which bevel pinion on the crank shaft is put in gear.

35 Now consider the method of removing a scoopful of earth, assuming the scoop to be hanging inverted in the right hand reversing place by the right hand hauling rope. Lower the scoop by this rope so that the 40 front wheels will travel down the runway so that the mouth of the scoop will be facing the excavation. Lower the runways or move the machine forward so that there will be sufficient earth available for the scoop 45 to cut in its passage across the channel. Draw the scoop from right to left by the left hand rope, until the front wheels of the scoop reach the lower left hand corner of the runway at the left hand reversing 50 place. Continue hauling on the left hand hauling rope until the back of the scoop rises until it is hanging inverted over the left hand embankment completing the operation of removing a scoop full of earth.

55 The reversing places N , referred to consist of vertical side plates rigid with and rising from runway channel irons W , and having bottom rails n in longitudinal continuation of the lower rails of the channel 60 irons W , and vertical rails n' , extending upwardly from the outer ends of said rails n , and guard rails n^2 . Said rails n , n' , n^2 , are formed by lateral flanges at the inner sides of the plates N . Each reversing place 65 is formed by a pair of these enlarged verti-

cal plates N , forming continuations and enlargements at the outer ends of the pair of channel irons forming a runway W . The rails formed by the flanges at the edges of said plates are arranged to permit the scoop to swing to the various positions described, between the two upright plates N , and to confine the scoop to the desired movements and against dislodgment and to guide the scoop back into the channels of runway W , 75 as the scoop makes its return movement.

As the scoop S reaches the dumping position, the front wheels s , will engage the vertical flanges n' , when the rear wheels of the scoop have passed between said plates N , and continued outward movement of the scoop will thereby be prevented so that continued pull of the hauling rope attached to the rear end of the scoop will cause this scoop to swing on the axis of wheels s , to the vertical position shown by dotted lines at the right of Fig. 1, with the rear wheels against the flanges n' .

The guard flange n^2 confines the truck carrying the scoop against upward movement from the space between the two vertical plates N and serves to guide the truck carrying the scoop as it swings in reversing. When the scoop starts on its return movement, the lower, front, wheels will travel down the flanges n while the upper wheel will travel down along the vertical flanges n' , until both sets of wheels are traveling on their flanges n , from which the wheels pass into the channel irons forming runway W . 100

In Fig. 4, the single acting scoop S mounted on wheels s is shown in full lines carrying a load, in dotted lines returning empty, and in inverted position at each reversing place with the runway frame G and the runways W pivoted on struts H at the right hand side and mounted on struts H^1 pivoted at h^1 fitted with racks R on the other side, meshing with pinions r . 105

Any suitable gearing or other means can be provided for actuating and controlling pinions r .

The axles as A with wheels as B , the struts as H connected to the runway frames in bearings at the pinions r , and the runway frames G form triangular frameworks, connected at the hinges as h , the hinges as h^1 and the bearings at the parts where the pinions r gear with the racks R on the struts H^1 so as to hold the machine together in any position of elevation desired. The runways W are raised so that they may clear the ground for moving forward for making the first cut and are lowered by 120 means of the rack R and pinions r so as to make successive cuts to the full depth.

Further both the side frames may be mounted on vertical racks H^1 (as shown in Fig. 5) said rack being held vertical by 125

guides h^2 and having a forked bearing h^3 at their lower ends to carry the wheels B.

The process of removing a scoop full of earth with the single acting scoop with two ropes is precisely as described for the double acting scoop, but the scoop is so formed as shown that on the passage when empty it does not project much if at all below the runways and therefore clears the ground 10 on the passage when not required to cut.

The single acting scoop with three ropes is hauled by the main hauling rope Z tilted forward by the tipping rope Z^1 and hauled back by the back-hauling rope Z^2 , the ropes 15 Z^1 and Z^2 being attached at the back of the scoop. The scoop passes across the cutting each way in the same position as the single acting two rope scoop, that is bottom down when filling, bottom up when 20 turning empty.

The single acting machine pivoted at one side of the cutting and raised and lowered only at the other side of it is operated in the manner already described, but it is adjusted vertically for successive cuts by 25 lowering it on the longer struts H^1 and for different depths of channel by the struts H.

It will be evident that other well known means may be adopted for raising and lowering the runways and for propelling the machine, and that it may move on slides or on wheels on the ground, or on rails, or be mounted on a floating pontoon.

Having now described my invention, 35 what I claim as new and desire to secure by Letters Patent is:

1. In an excavating machine of the class described, a scoop mounted on wheels, runways in which said scoop is reciprocated, 40 and reversing places forming enlargements of the ends of said runways in which said scoop is reversed.

2. In combination, in excavating apparatus, runways, supporting means therefor, said runways having end enlargements forming reversing places, a reversible scoop 45 movable back and forth longitudinally of said runways and provided with supporting wheels confined to travel in said runways 50 and to said end enlargements therefor, and operating cables for propelling and reversing the same, substantially as described.

3. In an excavating machine in combination, with runways and means for supporting the same, reversing places connected to 55 the ends of said runways, a scoop mounted on wheels adapted to travel in said runways, means for reciprocating said scoop in said runways, means for overturning said scoop 60 and wheels in said reversing places so as to reverse said scoop and wheels for making successive passages to and fro along said runways.

4. In an excavating machine of the class 65 described, in combination, runways having

reversing places connected to the ends thereof and formed by vertically disposed enlarged portions of the runways, a scoop with wheels adapted to travel in said runways and reversing places, and means for operating 70 the scoop.

5. In an excavating machine of the class described, in combination with runways, a scoop mounted on wheels and traveling in said runways, ropes for operating said scoop, 75 said scoop having a closed rear end and being reversible and said ropes applied at the rear of said scoop.

6. In combination, in an excavating machine of the class described, means for supporting and moving said machine, runways carried thereby, a scoop mounted on wheels and said scoop and wheels reversible and adapted to travel in said runways, cables applied to said scoop for hauling said scoop 80 rightwardly and leftwardly, and means for overturning and reversing said scoop and wheels.

7. In combination, in an excavating machine of the class described, means for supporting and moving said machine, runways supported thereby, a scoop mounted on wheels adapted to travel in said runways, means for hauling said scoop rightwardly and leftwardly and means for overturning 90 and reversing said scoop, comprising operating cables and upwardly extended enlargements at the ends of the runways.

8. In an excavating apparatus, in combination, parallel runways spaced a distance 100 apart, supporting means therefor, said runways provided at their outer ends with upwardly projected extensions forming approximately vertical tracks open at their inner sides, a scoop having a closed rear end, 105 a wheeled truck carrying said scoop and movable longitudinally of said runways and reversible at said vertical tracks, and operating cables for propelling said truck and for reversing the same, substantially as described.

9. In an excavating apparatus, in combination, parallel runways spaced a distance apart and at their ends provided with upwardly extending enlargements forming continuations of said runways, a wheeled truck arranged between and traveling along said runways and adapted to enter said enlargements and to reverse therein by overturning, a scoop carried by said truck and fixed with relation thereto, and operating cables for propelling said truck and bodily overturning the same with said scoop in said end enlargements.

10. In combination, a runway, a scoop provided with wheels adapted to be reciprocated longitudinally in said runway, means at the terminals of said runway whereby said scoop and wheels may be reversed, said means comprising vertically disposed por- 125

tions upon which said scoop is raised and downwardly extending portions adapted to guide said scoop in its return to said runway in reverse position, and means for operating said scoop.

11. In combination in an excavating machine, a runway, a scoop adapted to be drawn back and forth in said runway, said runway terminating at its end in vertically disposed guiding and reversing means, operating means for said scoop comprising cables fastened to the rear thereof and adapted to draw said scoop back and forth in said runway and to draw said scoop to reverse position within said guiding and reversing means.

12. In combination, in an excavating machine, a runway, reversing means fastened

to each of the ends of said runway, a scoop open at one end and provided with wheels whereby said scoop may be reciprocated longitudinally in said runway, cables fastened to the rear end of said scoop and adapted to draw said scoop in said runway and into the reversing means at the end thereof, said scoop adapted to be pivoted on its forward wheels within said reversing means and then drawn over by one of said cables to reverse position.

In testimony whereof I have signed my name to this specification in the presence of two subscribing witnesses.

GEORGE HENRY DUNLOP.
